(57) **CLAIM**

The ornamental design for a mechanically assisted device handle, as shown and described.

DESCRIPTION

FIG. 1 is a perspective view of a mechanically assisted device handle.

FIG. 2 is a second perspective view of the mechanically assisted device handle of FIG. 1.

FIG. 3 is a front view of the mechanically assisted device handle of FIG. 1.

FIG. 4 is a back view mechanically assisted device handle of FIG. 1.

FIG. 5 is a left side view of the mechanically assisted device handle of FIG. 1.

FIG. 6 is a right side view of the mechanically assisted device handle of FIG. 1.

FIG. 7 top view of the mechanically assisted device handle of FIG. 1.

FIG. 8 is a bottom view of the mechanically assisted device handle of FIG. 1.

FIG. 9 is a perspective view of the trigger portion of the embodiment of the mechanically assisted device handle of FIG. 1, shown separately for ease of illustration.

FIG. 10 is a second perspective view of the trigger portion of FIG. 9.

FIG. 11 is a front view of the trigger portion of FIG. 9.

FIG. 12 is a top view of the trigger portion of FIG. 9.

FIG. 13 is a bottom view of the trigger portion of FIG. 9.

FIG. 14 is a left side view of the trigger portion of FIG. 9.

FIG. 15 is a back view of the trigger portion of FIG. 9.

FIG. 16 is a right side view of the trigger portion of FIG. 9.

FIG. 17 is a perspective view of the cap portion of the embodiment of the mechanically assisted device handle of FIG. 1, shown separately for ease of illustration.

FIG. 18 is a second perspective view of the cap portion of FIG. 17.

FIG. 19 is a front view of the cap portion of FIG. 17.

FIG. 20 is a top view of the cap portion of FIG. 17.

FIG. 21 is a bottom view of the cap portion of FIG. 17.

FIG. 22 is a left side view of the cap portion of FIG. 17; and, FIG. 23 is a right side view of the cap portion of FIG. 17.

1 Claim, 8 Drawing Sheets
